SNAP FASTENER INSTALLATION

Walter I. Jones, Arlington, Mass., assignor to
United-Carr Fastener Corporation, Cambridge,
Mass., a corporation of Massachusetts

Application November 7, 1930, Serial No. 493,972

3 Claims. (Cl. 45—138)

My invention aims to provide improvements in snap fastener installations, particularly with reference to upholstery installations.

In the drawing, which illustrates a preferred embodiment of my invention,

Fig. 1 is an elevation view of a portion of an upholstery panel as viewed from the inner side thereof and showing the snap fastener members in place;

10 Fig. 2 is an enlarged section taken on the line 2—2 of Fig. 1; and

Fig. 3 is a section taken on the line 3—3 of Fig. 2.

My invention as illustrated by the drawing is directed to improvements in upholstery installations in which the upholstered panel is secured to the frame by separable fastening means, and is particularly directed to the idea of providing means whereby the fastener members carried by the upholstered part may be attached and detached readily without disturbing the covering means.

15 In the drawing I have shown a portion of a thin frame structure 1 having an aperture or apertures 2, as the case may be, to which is secured an upholstery panel 3 by means of snap fastener studs 4 as shown in Fig. 2.

The upholstery panel comprises a backing 5 of cardboard or the like to the edges of which are 20 attached metallic strips 6 and a flexible covering of fabric 7. If desirable a padding 8 (Figs. 2 and 3) may be used between the backing 5 and fabric 7. The fabric 7 is wrapped over the edges of the backing 5 and the strips 6 (Fig. 1) and is secured 25 in place by any suitable means.

Since it is an object of my invention to attach or remove the studs 4 without disturbing the fabric 7, I have offset a portion 9 of a strip 6 so as to be spaced away from the backing, and 30 apertures 10 in the form of elongated slots are provided in the portion 9 to receive the bases of the studs. The apertures 10 extend to the free edge of the portion 9 so that the studs may be 35 attached or detached by a lateral movement transverse to a strip, as will be apparent from an inspection of Figs. 1 and 3. The corners 12—12 of the metal strip adjacent to an aperture are bent upwardly to provide guides for the base 13 of the stud to guide it beneath a strip 6.

40 Detent means in the form of bosses 14—14 are provided in the metal strip adjacent to each aperture 10. These bosses extend toward the backing 5 so that when the base 13 of a stud is forced past them they will prevent accidental 45 displacement of a fastener member after it has

been attached and before the panel has been attached to the frame structure. Thus the studs are held in place by their bases and it is not necessary to form any holes in the backing part 5.

When the studs are attached as illustrated and described each has a boss portion extending through an aperture 10 to provide a yieldable head 15 and neck 16 for engagement in the aperture 2 in the frame part 1, as shown in Fig. 2. Furthermore the usual clearance is provided so that the studs may shift laterally in all directions relative to the upholstered part for alignment with their cooperating apertures in a frame part.

While I have shown a metal strip 6 for receiving the fastener stud it should be understood that cardboard or other suitable material may be used in the same manner and instead of providing a strip short pieces may be used where it is desired to locate the fasteners. However, the scope of my invention is best defined by the following claims.

I claim:

1. A snap fastener installation comprising in combination a frame structure, a part to be secured to said frame structure and snap fastening means securing said part to said frame structure, said part including a backing of relatively stiff material, a metallic edge strip secured to the backing adjacent to the edge at the rear face and having an aperture therethrough extending to one edge of the edge strip, said strip formed to be spaced from said backing adjacent to said aperture, a snap fastener member having a base located in the space between said backing and said strip, and means extending into the space between the strip and the backing to prevent accidental disassembly of the fastener member from the said part.

2. A snap fastener installation comprising in combination a frame structure, a part to be secured to said frame structure and snap fastening means securing said part to said frame structure, said part including a backing of relatively stiff material, a metallic edge strip secured to the backing adjacent to the edge at the rear face and having an aperture therethrough extending to one edge of the edge strip, said strip formed to be spaced from said backing adjacent to said aperture, a snap fastener member having a base located in the space between said backing and said strip, means extending from said strip into the space between the strip and the backing to prevent accidental disassembly of the fastener member from the said part, and upwardly bent por-

tions at the corners of said strip adjacent the aperture to facilitate lateral entrance of the fastener member base into the space between the strip and the backing.

5 3. A snap fastener installation comprising, in combination, a frame structure having an aperture presented thereby, a part to be secured to said frame structure, said part including a backing of relatively stiff material, a fastener-attaching means secured to the backing adjacent to the edge at that side facing the frame structure, said fastener-attaching means having an aperture therethrough extending to one edge thereof and a snap fastener member having a base located 10 between the fastener-attaching means and the backing and having a yieldable shank extending

from the base through the aperture in the fastener-attaching means and into engagement with the aperture in the frame structure thereby to secure the parts of the installation together, and said snap fastener member being adapted to be 80 engaged with and disengaged from the fastener attaching means by lateral movement thereof relative to the fastener-attaching means due to the aperture therein being extended to the edge thereof and detent means forming a part of the 85 installation to cooperate with the fastener member when it is in position to prevent accidental displacement from the fastener-attaching means.
